UNITED STATES PATENT OFFICE.

ADOLPH PETELE, OF FREEPORT, NEW YORK.

LIFTING-JACK.

1,393,242.

Specification of Letters Patent. Patented Oct. 11, 1921.

Application filed March 25, 1920. Serial No. 368,779.

To all whom it may concern:

Be it known that I, ADOLPH PETELE, a citizen of the United States, residing at 147 Denhoff avenue, Freeport, county of Nassau, 5 and State of New York, have invented certain new and useful Improvements in Lifting-Jacks, fully described and represented in the following specification and the accompanying drawings, forming a part of 10 the same.

This invention relates to that class of lifting-jacks in which a toothed lifter-bar is operated by a lifting-pawl and a holding-pawl or detent; and the object of the invention is to furnish means actuated by the hand-lever of the jack for raising the lifter-bar step by step, or lowering it step by step, or dropping the bar entirely.

The invention comprises a bell-crank pivoted adjacent to the detent and constructed to engage a stud upon the detent, and a reverse crank pivoted by the side of the lifting-pawl and having a body by which it can be moved, and an arm to contact with the bell-crank for retracting the detent in lowering the rack-bar.

The construction is such that a stud upon the lifting-pawl may act upon the reverse crank and impart an accelerated and multiplied movement to the detent by its bell-crank.

The construction and operation of these parts will be understood by reference to the annexed drawing, in which Figure 1 is a side elevation of a jack provided with the improvement, and the cover-plate of the casing removed; Fig. 2 is a section of the casing on line 2-2 in Fig. 1; Fig. 3 is a diagram showing the adjustment of the parts for 35 lowering the rack-bar step by step; Fig. 4 is a diagram showing the adjustment of the parts to wholly retract both pawls, so as to permit the free movement of the rack-bar by hand; Fig. 5 is a section of the casing taken on line 5-5 in Fig. 4; and Fig. 6 is a section of the casing taken on line 6-6 in Fig. 4.

A designates the standard of the jack with casing B at the top, and the rack-bar C slides 50 through the same.

A hand-lever D is pivoted in the lower corner of the casing and carries the lifting-pawl a. The holding-pawl or detent b is pivoted upon a fixed pivot c in the upper 55 part of the casing.

The pawls shown in Figs. 2 and 5 lie in one side of the casing and are separated by a partial partition f from a space g in the opposite side of the casing, in which the mechanism is mounted for varying the adjustment of the parts to raise, lower, or drop the lifter-bar. 60

A stud a' projects from the pawl a into the space g and a reverse crank is pivoted upon a pivot k in such space, and its body E extended across the side of the pawl a to coöperate with the stud. Its outer end projects beyond the casing to form a handle for moving it as desired. 65

This member is termed a reverse crank because it is used to reverse the action of the hand-lever upon the rack-bar, but it acts as any other bell-crank, as it receives motion by the arm E and transmits motion by the arm h. The bell-crank is therefore associated with each of the pawls, but the one associated with the lifting-pawl is termed a reverse crank to distinguish it from the one journaled with the detent upon the pivot c. 70

A spring e presses the pawl a normally into the rack-teeth C'. 75

A bell-crank having arms o and o', is journaled upon the pivot c of the detent, and a stud b' projects from the detent across 80 the plane of the bell-crank, as shown in Figs. 2 and 5. A spring e' is applied to the pivot c and the stud b' and presses the detent b normally toward the teeth of the rack-bar. A spring e² is applied to the bell-crank 85 and the pivot c to press the arm o' forcibly toward the stud b' of the detent, the spring of the bell-crank being made stronger than the spring e' of the pawl, so that the bell-crank when unrestrained presses the detent 90 away from the rack-bar. 95

The arm o of the bell-crank extends toward the reverse crank E, which is also of right-angle or bell-crank form and has a lever-arm h directed toward the detent so as 100 to contact with the arm o, when the body of the reverse crank is swung downwardly, as shown in Fig. 1. The arm h in such case rotates the bell-crank upon the pivot c and retracts it from contact with the stud b' of 105 the detent, thus leaving the detent free to press into the teeth of the rack-bar.

It will be noticed in the drawing, that the arm o is made very much shorter than the arm h so as to multiply the angular move- 110

ment imparted to the bell-crank. The stud a' operates upon the reverse arm E close to its pivot h thus causing a short movement of the stud to move the arm h through a considerable arc.

This construction of the parts enables the very first downward movement of the pawl a to effect an entire release of the detent, which permits it to promptly engage the nearest tooth upon the rack-bar.

The body of the reverse crank projects through a slot in one edge of the casing, and may be locked in its lower position by contact with a shoulder i upon the side of the slot. The top of the slot forms an upper stop j .

A spring l is applied to the pivot h and the arm h of the reverse crank to press such arm normally away from the arm o of the bell-crank, and operates to press the body E against the upper stop j when the reverse crank is not locked in its lower position. The spring l yields in lowering the rack-bar step by step, as the stud a' upon the lifting-pawl contacts with the body E and depresses it at each downward movement of the pawl, as hereinafter described.

Operation of the device.

30 The reverse crank is locked in its lowest position for raising the rack-bar step by step, as such adjustment presses the arm h against the arm o of the bell-crank and retracts the arm o' from the stud of the detent as shown in Fig. 1, leaving the detent free to move under the control of its spring e' , when catching each tooth of the rack as they are successively raised by the lifting-pawl.

40 The reverse crank remains stationary during such use of the jack, and the stud of the lifting-pawl does not contact at all with the body of the reverse crank.

In lowering the rack-bar step by step it is necessary to engage the detent with the rack-teeth while the load is resting upon the lifting-pawl, and this is effected by unlocking the reverse crank and leaving it to move upward and downward under the control of the stud a' and the spring l .

Under these conditions, the stud a' when the lifting-pawl is moving downward, contacts with the body E of the reverse crank close to its fulcrum, thus tipping or rocking the reverse crank momentarily, so that its arm h moves the bell-crank from the position shown by full lines in Fig. 3 (in which position it holds the detent from engagement with the rack) to the position shown in dotted lines, in which the detent is left free under the control of its spring e' to engage the successive teeth of the rack.

A clearance notch m is cut in the top of the reverse bell-crank adjacent to the point where the stud a' presses upon such body,

and the continued downward movement of the lifting-pawl when the rack is arrested by the detent causes such lifting-pawl to slide outwardly upon the rack-teeth and bring the stud a' over the notch m . This removes the pressure of the arm h upon the bell-crank, and leaves the reverse crank free to move under the control of its spring l .

This action of the stud a' upon the reverse crank occurs when the rack-bar is carrying a load, but when it is carrying no load the lifting-pawl does not exert sufficient pressure upon the body of the reverse crank to turn it upon its pivot against the resistance of the bell-crank.

The spring e^2 of the bell-crank is made to exert a considerable force to overcome the resistance of the pawl-spring e' , and the bell-crank therefore remains stationary under these conditions, holding the detent out of engagement with the rack as shown in full lines in Fig. 3.

When the lifting-pawl draws out of the rack-teeth (when moved downward by the hand-lever) the rack is immediately freed from both of the pawls and may be moved upward or downward freely by hand without opposition from the pawls.

It will be observed that the bell-crank and reverse crank act directly by pressure upon one another, and wear and friction are thus avoided which arise when sliding contacts are employed. Thus, the bell-crank pushes directly against the stud b' (in retracting the pawl b) and the arm h presses directly against the bell-crank arm o in retracting the pawl b from the rack-teeth.

It will be observed that all the springs likewise press directly against the parts that they move, and are made of spiral coils which are cheaper and retain their elasticity for a longer time than flat leaf-springs, and have a greater range of movement.

The prime object of my invention is to change the detent from an inoperative position (retracted from the rack-teeth) quickly to an operative position in readiness to engage any of the rack-teeth by releasing the detent quickly from the mechanism which holds it inoperative.

The invention differs from others in having a bell-crank associated with the detent and a bell-crank also associated with the lifting-pawl, the latter being so connected with the former as to produce an increased and accelerated movement of the bell-crank which holds the detent inoperative. This movement of the bell-crank releases the detent instantly upon the downward movement of the lifting-pawl to engage a succeeding tooth of the rack.

The construction is very cheap, as there are only two principal parts employed to operate the pawls, namely, the bell-crank and the reverse-crank, which are readily

stamped of flat sheet steel in the exact form required.

The operative mechanism can, without any other change, be proportioned to actuate a jack of any desired size, large or small.

It is common in lifting jacks having a toothed rack to use a lever with a lifting pawl and to provide a detent for supporting the load, and means whereby the pawl and detent are operated reversely in raising and in lowering the rack.

Such parts are therefore public property, and my claims as in other patents upon lifting jacks cover the combination and arrangement in which my construction differs from those heretofore used.

Having thus set forth the nature of the invention what is claimed herein is:

20 1. A lifting-jack having a toothed lifter-bar, a holding detent having a stationary pivot and side stud, a hand-lever with lifting-pawl pivoted thereon, a bell-crank journaled upon the pivot of the detent *a* having a long arm and spring to hold the detent in an inoperative position and a short arm for actuation, a reverse crank extended by the side of the lifting-pawl and having a multiplying arm much longer than that upon the bell-crank to multiply the movement of the bell-crank, a stud projected from the lifting-pawl into the plane of the reverse crank and operating when the pawl is moved downward to press upon the reverse crank and turn its multiplying arm against the arm of the bell-crank, all constructed and operated substantially as set forth.

25 2. A lifting-jack having a toothed lifter-bar, a holding-pawl or detent *b* having a stationary pivot, a hand-lever with lifting-pawl pivoted thereon, a bell-crank journaled upon the pivot of the detent and provided with a spring for holding the detent in an operative position, a reverse crank pivoted adjacent to the side of the lifting-pawl and having an arm to actuate the bell-crank, and means for locking the reverse crank with the bell-crank in an inoperative position.

30 3. A lifting-jack having a toothed lifter-bar, a holding pawl or detent having a sta-

tionary pivot *c*, a hand-lever *D* with lifting-pawl pivoted thereon, a bell-crank journaled upon the pivot *c* of the detent and having an arm *d'* and spring *e'* to hold the detent in an inoperative position, and a short arm for actuation, a free-moving reverse crank *E*, *h*, extended by the side of the lifting-pawl *a* and having an arm much longer than that upon the bell-crank to multiply the movement of the bell-crank, a stud *a'* projected from the lifting-pawl into the plane of the reverse crank arm *E* and operating when moved downward to press upon the reverse crank, the latter having a notch *m* to clear the stud when the lifting-pawl *a* is wholly lowered, in the operation of releasing the lifter-bar, all constructed and operated substantially as set forth.

35 4. A lifting-jack having a toothed lifter-bar, a casing with hand-lever pivoted thereon, and a lifting-pawl with journal on said lever, a fixed pivot-bearing above said journal with a detent pivoted thereon, a reverse lever extended across the lifting-pawl and pivoted upon the casing at the side of the lifter-bar, and having a crank-arm projected toward the detent, and a bell-crank pivoted upon the journal of the detent, with a short arm to engage the arm of the reverse crank, and a longer arm to detachably engage the detent and control its engagement with the lifter-bar.

40 5. A lifting-jack having a toothed lifter-bar, a casing with hand-lever pivoted thereon, and a lifting-pawl with journal on said lever, a fixed pivot-bearing above said journal with a detent pivoted thereon, the pawl and detent being provided each with a side stud, and bell-cranks pivoted adjacent to the pawl and detent, and having a long arm upon one operating with a short arm on the other, to release the detent for action upon a slight movement of the lifting-pawl, the bell-cranks controlling the movement of the pawl and detent by contact of the bell-cranks with their adjacent studs.

In testimony whereof I have hereunto set my hand.

ADOLPH PETELER.
